UNITED STATES PATENT OFFICE.

RICHARD E. A. DE BOW, OF BRADLEY BEACH, NEW JERSEY.

NAIL-SET.

1,112,056.

Specification of Letters Patent.

Patented Sept. 29, 1914.

Application filed July 8, 1913. Serial No. 777,938.

To all whom it may concern:

Be it known that I, RICHARD E. A. DE Bow, citizen of the United States, residing at Bradley Beach, in the county of Monmouth and State of New Jersey, have invented certain new and useful Improvements in Nail-Sets, of which the following is a specification.

My invention relates to carpenters' tools, 10 and particularly to nail sets.

The object of my invention is to reduce to a minimum the splitting and marring of woodwork when the woodwork is being removed for repairs. When it is desired to remove woodwork it is necessary to drive the 15 nails holding the woodwork in place entirely through the work so as to permit the removal of the wood without splitting or marring it. The nails are driven through the 20 piece of wood by means of nail sets. The ordinary nail set has a shank which is tapered adjacent one end, this tapered shank being perfectly smooth from the greatest diameter of the taper down to the smallest 25 diameter thereof. When a nail-set of this character is driven into a piece of woodwork to force the nail through the woodwork it is difficult to withdraw it. It is necessary to hammer it or work it from side to side, there- 30 by making a relatively large hole in the woodwork before the nail-set can be liberated.

The object of my invention is to provide a nail-set so formed that it may be removed 35 without working it from side to side and thereby enlarging the hole made by the set and by the nail. For this purpose I have devised the construction illustrated in the accompanying drawings, wherein:—

40 Figure 1 is an enlarged view of a nail-set constructed in accordance with my invention. Fig. 2 is a longitudinal section thereof.

Corresponding and like parts are referred to in the following description and indicated 45 in all the views of the accompanying drawing by the same reference characters.

Referring to these drawings 2 designates the shank of a nail-set which is cylindrical in form and is preferably knurled, the upper 50 end of the nail-set being smooth as at 3. Below the knurled portion of the shank 2 the shank is tapered as at 4. The lower extremity of the set is slightly concaved as at 5 to form a seat for the nail-head.

55 My invention consists in forming screw-

threads 6 upon the tapered portion of the nail set, these screw threads extending from the upper end of the tapered portion 4 nearly to the lower end thereof, the small end of the nail set being left smooth as at 7, 60 inasmuch as the screw threads at the small end do not materially engage the work or secure any particular advantage.

The upper end of the nail-set is provided with a transverse handle bar 8 which is so 65 disposed as not to interfere with the driving in of the nail-set and which at the same time will form a handle whereby the nail-set may be held and also form a handle whereby the nail-set may be unscrewed after it is 70 driven in.

The operation of my invention will be obvious to those skilled in the art of carpentry.

When it is desired to drive a nail into a piece of wood so that its head shall be beneath the surface of the wood, the nail-set is used in the ordinary manner, the concaved end 5 being placed in contact with the head of the nail. When it is desired to drive the nail entirely through the wood, however, so 80 as to permit the removal of the wood without splitting or marring it, the end of the nail-set is held against the head of the nail and the nail set is driven inward driving the nail in through the wood to be removed. 85 Thus, for instance if the plank to be removed is an inch in thickness the nail set will be driven into the plank one inch. When it is desired to remove the nail set it is only necessary to rotate it, which will cause 90 the screw threads 6 to engage the wood surrounding the nail set and the nail set may be readily removed. The opening through which the nail set is removed will be only as large as the opening formed by the nail set 95 and will not be enlarged by working the nail set laterally as would ordinarily be the case with a nail-set unprovided with the screw threads 6. The cross bar 8 at the butt end of the set not only permits the set to be rotated to thus remove it but also acts as a 100 guard for the fingers, protecting them from injury when hammering the nail-set in. The advantages of my invention will be apparent from what has gone before, and 105 while I have illustrated a nail set having a certain definite form I wish it to be understood that the principle of my invention might be applied to nail sets having other forms.

Having thus described the invention what is claimed as new is:—

1. As an article of manufacture, a nail set having a shank tapered adjacent one end, the butt end of the tapered portion being of the same diameter as the body of the nail set, said shank being screw threaded along the tapered portion thereof, said screw threads being relatively shallow.
2. As an article of manufacture, a nail set having a shank tapered adjacent one end,

the tapered portion of the shank having shallow screw threads formed therein, the smallest portion of the shank being blunt and adapted to engage the head of a nail.

15

In testimony whereof I affix my signature in presence of two witnesses.

RICHARD E. A. DE BOW. [L. s.]
